UNITED STATES PATENT OFFICE.

GRABLE B. WEBER, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ATTACHMENT PLUG.

Application filed May 28, 1920. Serial No. 384,864.

To all whom it may concern:

Be it known that I, GRABLE B. WEBER, a citizen of the United States, residing at Chicago, in the county of Cook and State of Illinois, have invented new and useful Improvements in Attachment Plugs, of which the following is a full, clear, concise, and exact description, reference being had to the accompanying drawing, forming a part of this specification.

My invention relates to attachment plugs, and more specifically to attachment plugs for heavy duty, in which provision has to be made to prevent injury to the contact due to the heavy current.

One of the objects of my invention is to provide an improved plug for heavy duty in which provision is made for preventing injury to the contact and making the connection. I accomplish this by providing a switch mechanism carried by the plug, which switch mechanism is automatically moved to "on" position when the plug is inserted into the receptacle.

Further objects will appear from the description to follow and from the claims.

In the drawings, in which an embodiment of my invention is shown—

Fig. 1 is an axial section of an attachment plug on the line 1—1 of Fig. 2;

Fig. 2 is an axial section on the line 2—2 of Fig. 1;

Fig. 3 is a section on the same plane as Fig. 1 but showing the center contact switch pushed in; and

Fig. 4 is a side elevation of a part of the plug with the threaded shell contact removed.

In order to give a general idea of the construction shown, it is here stated that it comprises a swivel plug for screwing into an Edison socket, the swivel shell contact of the plug being provided with a thumbpiece or handle member, the plug itself containing a switch mechanism or circuit controller actuated by the center contact of the plug, and being provided with binding terminals for conductors leading from the plug, and with cord-grip means for relieving these binding terminals from strain due to a pull on the conductors.

Referring now to the construction in detail, the plug shown comprises an insulating base 15, a center contact 16 supported thereby, a swivel shell contact 17 rotatably

mounted with respect thereto, a thumbpiece or handle 18 connected with the swivel shell contact 17, a switch mechanism or circuit-controlling device 19 mounted in the insulating base 15, binding terminals 20 and 21 for the conductors leading from the plug respectively, and an insulating screw cord-grip member 22 for gripping the conductors to relieve the binding terminals 20 and 21 from strain.

Referring particularly now to the construction of the switch mechanism or circuit-controlling mechanism 19, this comprises an insulating push-button member 23, which is slidably mounted in the insulating base 15, and carries the center contact 16, a pair of movable spring contact members 24, actuated by the push button member 23, and an annular contact member 25 with respect to which the contact members 24 are moved into and out of engagement. The annular contact member 25 has a formed integral therewith the downward extension 26, into which the binding screw of the binding terminal 20 is screwed.

The center contact 16 has a shank portion 27 which extends down through the push button 23. In order to provide guide means for the lower end of this shank 27, it may be made to extend through an eyelet portion 28, this eyelet portion 28 being formed as an integral part of a stamping from which the contact members 24 are also formed. This eyelet thus serves not only to guide the lower end of the shank 27, but also to secure the contact fingers 24 in place. This eyelet portion is secured to an insulating disc 29, which in turn is secured to the insulating base 15.

A coil compression spring 30 is provided which normally holds the plunger 23 and contact 16 in extended position. This plunger 23 is provided with an annular enlargement 31, the lower face of which forms a conical cam for cooperation with the spring contact fingers 24. When the plug is not connected, the coil compression spring 24 will hold the plunger 23 in extended position, and the spring contact fingers 24 will then be in the position shown in Fig. 1. However, when the plug is screwed into the socket, the center contact 16 and plunger 23 will be moved to a position shown in Fig. 3, and the conical cam face of the enlargement 31 will force the spring contact fingers 24

out of engagement with the annular contact member 25, and thus complete the circuit between the center contact 16 and the binding terminal 20.

5 The electrical connection between the threaded shell contact 17 and the binding terminal 21 is effected by means of an annular sliding contact member 32, which has a shoulder portion 33 cooperating with the shoulder portion 34, formed integrally with the threaded shell contact 17. The sliding contact member 32 has an upstanding annular flange portion 35, to which is secured the binding plate conducting member 36 in 10 which the binding screw of the binding terminal 21 is threaded. The sliding contact member 32 not only serves to electrically connect the threaded shell contact with the binding terminal 21, but also serves to hold 15 the insulating disc 29 in place on the insulating base 15. Furthermore, the sliding contact member 32 is formed as an integral part of a stamping which has a downwardly extending screw-threaded portion 37 into 20 which the cord-grip member 22 is threaded. The insulating disc 29 is provided with a pair of openings 38 through which the conductors are led respectively, the conductors being pinched or gripped between the upper edge of the cord-grip member 22 and the edges of the openings 38, when the cord-grip member 22 is screwed into the 25 threaded collar 37.

In wiring the device, the cord-grip member 22 is unscrewed from the threaded collar 37, the threaded contact 17 is slipped down off from the insulating base 15, the cord-grip member 22 and the threaded shell contact 17 are passed over the ends of the 30 conductors, and the conductors are passed up through the openings 38 and secured to the binding terminals 20 and 21 respectively. The threaded shell contact 17 is then slipped up in place on the insulating base 15 and the cord-grip member 22 is screwed up 35 to grip the cord and also to hold the threaded shell contact 17 in place.

Assuming that the plug is screwed into the socket and that the parts are therefore 40 in a position shown in Fig. 3, the circuit is from the center contact, through the shank portion 17, the eyelet portion 28, the spring contact fingers 24, the annular contact 25 and binding terminal 20 through 45 whatever translating device is connected with the plug to the binding terminal 21 thence through the sliding contact 32 to the threaded shell contact 17.

The manner in which the circuit controller 50 is operated has been outlined in connection with the description of the construction and is as follows: When the threaded shell contact 17 is screwed into a socket, the center contact 16 is thereby brought into engagement with the center contact of the socket, 55

but as the spring contact fingers 24 are not yet in engagement with the annular contact 25 there will be no current flowing. However, after the threaded shell contact is screwed in further, the center contact 16 70 and plunger 23 are moved inwardly with respect to the insulating base 15, and the cam portion of the enlargement 31 of the switch button will force the contact fingers 24 outwardly into engagement with annular 75 contact 25 and thus complete the circuit. This prevents any arcing between the contacts of the plug and the contacts of the receptacle.

Similarly when the plug is removed from 80 the socket, the coil compression spring 30 will keep the center contact 16 of the plug in engagement with the center contact of the receptacle until after the plunger 23 has been moved outwardly to permit the spring 85 contact fingers 24 to move away from engagement with the annular contact member 25. The circuit is therefore not broken between the plug contact and the receptacle contact but between the contacts which are 90 located inside the insulating base 15. Thus there is no danger of arcing between the plug contact and the receptacle contact.

Having thus described my invention, what I claim as new and desire to secure by Let- 95 ters Patent is:

1. An attachment plug comprising a body portion, a disc thereon, a contact member within said body, an eyelet in said disc, a contact finger secured to said disc by said eyelet, and means for causing said contact finger to engage said contact member comprising a plunger extending through said body portion and slidable in said eyelet. 100

2. An attachment plug comprising a body portion, a disc thereon having an opening therein, a plunger extending through said body portion, a center contact on said plunger having a shank thereon guided in said opening, and a contact finger supported by said disc, and means whereby said contact finger is controlled by said plunger. 105

3. A switch plug comprising an insulating base, a center contact member mounted for longitudinal movement thereon, a shell contact member swiveled therein, a wiring terminal provided with a contact member slidably engaged by said swivel shell, a second wiring terminal provided with a contact member and switch mechanism comprising a contact movably mounted on said insulating base and operated by said center contact for controlling the circuit between said center contact and the contact with which said second wiring terminal is provided. 115

4. A switch plug comprising an insulating base, a center contact member mounted for longitudinal movement thereon, a shell contact member swiveled therein, a wiring 120

- terminal provided with a contact member slidably engaged by said swivel shell, a second wiring terminal provided with a contact member and switch mechanism comprising a contact movably mounted on said insulating base and operated by said center contact for controlling the circuit between said center contact and the contact with which said second wiring terminal is provided, said movable contact comprising an elongated member extending longitudinally of the plug and swingable back and forth to engage and disengage the contact for the second wiring terminal.
- 5 15. A switch plug comprising an insulating base, a shell contact mounted therein, a center contact mounted for longitudinal movement thereon, wiring terminals mounted thereon for said contacts, respectively, and
10 20 means for controlling the circuit between one of said wiring terminals and one of said contacts comprising an elongated contact member located substantially within said threaded shell contact and extending longitudinally of the plug and swingable back and forth by means of a center contact.
- 25 6. A switch plug comprising an insulating base, a shell contact mounted thereon, said base having a central recess thereon and an opening at its entering end leading to said recess, a center contact member slidably mounted in said opening, and switch mechanism for controlling the plug circuit, said switch mechanism comprising a member located substantially within said threaded shell contact and mounted to swing back and forth in said recess and operated by said
30 35 slideable center contact member.

In witness whereof, I have hereunto subscribed my name.

GRABLE B. WEBER.
